UNITED STATES PATENT OFFICE.

MARTIN GERBER, OF IOWA CITY, IOWA.

RADIATOR-REPAIR MACHINE.

Application filed September 11, 1922. Serial No. 587,606.

To all whom it may concern:

Be it known that I, MARTIN GERBER, citizen of the United States, residing at Iowa City, in the county of Johnson and State of Iowa, have invented certain new and useful Improvements in Radiator-Repair Machines, of which the following is a specification.

This invention relates to radiator repair machines. More particularly, it belongs to 10 that class or type of work holders that are designed especially to receive the radiators of automobile motors after the radiators have been detached, and to support the radiators in various positions for convenience 15 of making repairs. This invention also belongs to that class of repair stands which are provided with a tank into which the radiator may be lowered to detect any leaks requiring attention.

20 The object of this invention is the production of an apparatus of the nature stated comprising parts of special construction and arrangement whereby it is believed an unusually strong, easily operated, cheap and 25 useful adjunct to a repair shop is provided for the purposes described.

In the accompanying drawings illustrating the construction and arrangement of the various parts of this invention, Fig. 1 represents 30 a front view of all parts assembled, portions being broken away to disclose the interior of the tank. Fig. 2 is a side view, with portions broken away to show internal members. Fig. 3 is a front view of one 35 end of the drip trough, showing its supporting bracket permitting it to be slipped in and out of position. Fig. 4 is a top plan view. Fig. 5 is a vertical section of one side of the turntable ring and of the vertically 40 movable frame carrying the ring, with the rollers providing for the horizontal revolution of the ring. Fig. 6 is a front view of the lower roller and a side view of the upper roller showing the block supporting the 45 rollers upon the movable frame. In Figs. 5 and 6 the scale of drawings has been increased to render the illustration clearer.

Throughout the description and drawings, the same letter is used to refer to the 50 same part.

Considering the drawings, the supporting structure or stand has the legs A and a, and a rectangular top B, provided with an inner portion b upon which the upper side 55 of the tank C is turned over as illustrated.

Transversely below the tank is the rocking

shaft D, having a foot lever d in convenient position, and an upwardly extending catch blade E, provided with spaced notches e. The blade E passes upwardly through the 60 plate F having a lug for engaging the notches, and the notches and lug may be disengaged by pressure of the foot upon the foothold f arranged immediately above the foot lever d. The lug plate F has a slot G 65 for the passage of the curved blade E, and the blade has a pivot g connecting it with the foot lever. It will be noted that the notches e are fashioned to prevent the blade E from rising through the slot G when the notches 70 and lug of plate F are disengaged, and the reason for such construction is that the weight of the radiator being worked upon would tend to raise the foot lever, as hereinafter more fully explained. To balance in 75 part the weight of the sustained radiator, the weight H is introduced. It is carried adjustably upon the arm h which is secured to the transverse rock shaft D.

As best illustrated in Fig. 2, there is attached to the rock shaft D a crank arm J, that has a pivotal connection with a rod i, which has in turn a pivotal connection with the vertically reciprocating post or tube K, passing through the cylindrical guide l, 80 erected upon the top B of the stand. It will be understood that, as illustrated there is a crank arm such as explained, with a connecting rod, and guided reciprocating tube on the other side of the machine. The construction and operation of these parts are in 85 all respects the same. The function of the reciprocating tubes such as K is to raise and lower a movable frame L, with which the tubes are connected by vertical rods such as 90 rod M, passing through the guide m, and inclined braces N and n, best shown in Fig. 2. The frame L is constructed to enter the tank, and it carries a turntable ring O. The ring is provided with cross-pieces or bridges P 95 and Q, as best shown in Fig. 4, which are the work rests, and the ring is horizontally revoluble upon the supporting rollers R, and the retaining or side rollers r, the latter being directly supported by the frame L, and the former by a block S attached to the frame. There may be any number of sets of rollers. In practice there are ordinarily 100 eight sets as delineated.

At the sides and towards the front of the 110 top B of the stand are erected the posts or tubes T, one on either side, reinforced by

the inclined braces *t*. These posts carry a vertically adjustable horizontal bar *U*, that may be supported in one or more different positions by pins such as the pin *u* engaging pinholes in the posts *T*. The bar *U* extends transversely above the frame and turntable, and at its ends is provided with the straps *V* and *v* which encircle the posts. The bar may be attached to a radiator to 10 additionally hold the same in a desired position. It is believed to be clear that if the bar *U* is thus attached to a radiator, the same may still be given a limited up and down movement, provided the pins *u* are 15 removed from the pinholes.

At the top, the posts or tubes *T* are bent in a forwardly direction, and each is attached to an upper cross bar *W*. This is a stationary bar. It supports the reflector *c* 20 by which the light of the lamps shown in Figs. 1 and 2 may be directed downwardly into the tank *C*. This invention is not intended to be restricted to the reflector or number of light bulbs illustrated, and the 25 reference letter *c* will be understood to designate a lighting device of any desired construction and arrangement for the purpose. In addition to the lights, the bar *W* supports the lever *w* best shown in Fig. 2, and the lever is adjustably held in either of a 30 number of different positions by means of the finger catch *X* that engages the notches in the quadrant *w* suitably arranged. The rear end of the lever *w* is connected with 35 the lighting device *Y* by the cords *y*, and the light *Y* may be raised or lowered to illuminate different portions of a radiator upon the turntable.

To catch water falling from the top *B* 40 of the stand, there is usually provided a drip trough *Z*, removably held in angle brackets *z*. The trough may be slipped out and cleaned at any desired time. In practice the trough *Z* is usually placed in communication with the tank *C* by means of the drip tube *L* shown in Fig. 2.

In the operation of this invention, assuming a radiator to have been placed upon the cross-pieces *P* and *Q* of the turntable ring, 50 it will be understood that by operating the foot lever the ring and its load may be lowered into the tank *C* to detect leaks in the customary manner, and by suitably engaging the notched blade *E* with the lug 55 plate *F* the radiator may be supported within the tank. It will also be noted that in the tank or out, the turntable may be revolved to bring any portion of the radiator within sight or reach, and if need be the interior 60 of the tank may be illuminated by the light from the reflector *c* mentioned. To render the labor of raising and lowering the radiator easier, the balancing weights *H* have been introduced.

65 In the drawings accompanying this ap-

plication the vertically reciprocating member *K*, and the side posts *T* are shown as being formed by tubes and tubular connections, but it is not intended to confine this invention to the use of tubular parts. 70

Having now described this invention and explained the mode of its operation, what I claim is:—

1. In a radiator repair machine, the combination with a stand, of a tank carried by 75 the stand, a frame constructed to enter the tank, means for raising and lowering the frame and for holding it in intermediate positions, and a turntable ring provided with cross-pieces and carried by the frame 80 and movable with the said frame into and out of the tank.

2. In a radiator repair machine, the combination with a stand, of a tank supported by the stand, a frame constructed to enter 85 the tank, means for raising and lowering the said frame and for holding it in intermediate positions, a table carried pivotally by the frame and movable with it, and a vertically adjustable bar arranged above the 90 said movable frame.

3. In a radiator repair machine, the combination with a stand of a tank supported by the stand, a frame constructed to enter 95 the tank, means for raising and lowering the said frame and for holding the same in intermediate positions, a turning table pivotally carried by the said frame and movable up and down therewith, and means extending over the said frame and carried by 100 the said stand to which a radiator may be fastened to be worked upon.

4. In a radiator repair machine, the combination with a stand, of a tank supported by the stand, a frame constructed to enter 105 the tank, means for raising and lowering the said frame and for holding the same in intermediate positions, a turning table pivotally carried by the said frame and movable up and down therewith, and adjustable lighting means whereby lights may 110 be directed upon different parts of a radiator borne by the said table.

5. In a radiator repair machine, the combination with a stand, of a tank supported by the stand, a frame constructed to enter 115 the tank, means for raising and lowering the frame and for holding it in intermediate positions, the said means including vertically reciprocating posts provided with inclined braces connected with the said frame to hold the frame horizontal, a turntable carried by the frame and movable with the frame into and out of the said tank, and a vertically adjustable support carried 120 by the stand and extending over the turntable.

In testimony whereof I affix my signature.

MARTIN GERBER.
